SAFETY LOCKING DEVICE FOR MANUALLY
OPERATED CIRCUIT BREAKERS

Carl P. Sorensen, Chicago, Ill.

Application January 9, 1952, Serial No. 265,647

12 Claims. (Cl. 200—42)

1

This invention relates broadly to circuit breakers and more particularly to novel locking means for circuit breakers.

In circuit breaker installations in general and particularly in panelboard and load center installations, it is often desired or imperative that the setting of a particular breaker or group of breakers remain undisturbed. Situations often occur in which a breaker or group of breakers have been set in "on" or "off" position with some important purpose in mind, and some unauthorized person either purposefully or inadvertently changes the settings of the breaker or group of breakers. Situations of this nature may result in annoying interruptions to service or operations, and may even cause serious damage to apparatus and injury to persons who may be relying on the setting of the breaker or group of breakers.

Heretofore in certain instances circuit breakers mounted in metal enclosures have been provided with a locking means for locking the breakers in set position. The form of locking means consisted of walls formed integral with the cover of the metal box enclosing the breaker and surrounding the slot provided in the cover for the manual operating member. Oppositely disposed openings were provided in the side walls to form staples for receiving the hasp of a padlock.

Since it could not be accurately foreseen whether any particular breaker would require a locking means, it was necessary to provide the metal box of each of a line of breakers with the locking means described above.

In panelboard installations involving a plurality of breakers, it has not been possible heretofore to prevent movement of the operating handle of any particular breaker except by providing a cover for the entire board and locking the cover in closed position. Accordingly, the primary object of my invention is to provide a novel and an improved form of a device for preventing movement of a circuit breaker control handle.

Another object of my invention is to provide an improved form of a device for preventing movement of the operating handle member of a circuit breaker, which is capable of being quickly and easily attached to or detached from the circuit breaker structure where said handle has a hole provided therein, or where a hole can be so provided.

Another object of my invention is to provide an improved form of attachment for preventing movement of the operating handle member of a circuit breaker which is adapted for use with

2

many types of electrical switches where the handle member has a hole provided therein or where it is possible to drill a hole.

Another object of my invention is to provide a locking device having associated parts including a locking bar for attachment to a circuit breaker structure for preventing substantial movement of the operating handle member thereof, and a padlock for preventing detachment of the device from the breaker structure.

Another object of the invention is the provision of a portable device of unitary structure for preventing substantial movement of the operating handle member of a circuit breaker, or any switch, having an opening in the handle member thereof.

A still further object of my invention is the provision of a device for preventing substantial movement of the operating handle member of a circuit breaker in which the device is provided with means for quick attachment to or removal from the circuit breaker structure and in which locking means are provided for preventing removal of the device from the circuit breaker structure.

A still further object of the invention is to provide a device which may be removably attached to a circuit breaker structure for preventing substantial movement of the operating member thereof and which functions as an indicator to indicate that the setting of the breaker is not to be disturbed.

A still further object of my invention is to provide a device attachable to a circuit breaker structure for preventing substantial movement of the operating member thereof, which is of simple and rugged construction and which can be manufactured and sold at a relatively low cost.

Generally, my invention consists of a bumper guard or an angle shape member of rigid material which is adapted to be placed in position in the rectangular shaped opening provided in the circuit breaker casing through which the operating member, or handle, of the breaker extends. The bumper guard, when mounted in position in the opening, has one portion which engages the end edge of the rectangular shaped opening and is provided with an angular extending portion for contacting the outwardly exposed surface of the operating handle of the breaker which extends outside the breaker casing and to prevent substantial movement of said handle. The position of the bumper guard may be reversed so that the operating handle of the breaker may be

held either in its open or closed circuit position. The operating handle of the breaker is provided with an opening, such as a drilled hole, extending therethrough parallel with its uppermost surface and extending in a direction which is in alignment with the movement of said handle. The angular or outwardly extending portion of the bumper guard also is provided with an opening, or drilled hole, said hole extending therethrough and in direct alignment with the opening in said handle. A shoulder pin is provided whereby it may be placed with its shoulder in contact with one side of said handle, so that the pin portion thereof will extend through the opening in the handle and then through the opening in the bumper guard with an end portion thereof extending outwardly from said bumper guard. A locking bar is provided with an opening therein through which said end portion of said shoulder pin will extend when said bar is placed over said pin and in contact with the outer surface of the bumper guard. Securing means is provided within said locking bar for rigidly securing said bar to said pin. A locking means is also provided in the form of a lock body and with a pivoted hasp, said hasp shaped to extend through a second opening in said locking bar preventing access to said securing means whereby said pin may not be removed from said bumper guard and said operating handle if it is not so desired.

Other objects and advantages, more or less ancillary to the foregoing and the manner in which all the various objects are realized will appear in the following detailed description and accompanying drawings wherein is assembled and pointed out certain details of structure and aggroupment of parts connotative of the scope of the invention as defined in the appended claims.

Referring to the drawings which illustrate the preferred embodiment of the invention:

Figure 1 is a vertical sectional view of a circuit breaker structure to which this invention can be attached, the circuit breaker being enclosed in a suitable box, the front cover and body of the box being shown in sections;

Figure 2 is a front view of the circuit breaker structure shown in Figure 1;

Figure 3 is a side view of a circuit breaker structure as shown in Figure 1, a portion of the side wall broken away and a portion of the cover shown in section, and said structure having one form of this invention shown attached thereto; the locking bar shown in section;

Figure 4 is a front view of the circuit breaker structure as shown in Figure 3 with one form of this invention shown attached thereto;

Figure 5 is a disassembled perspective view showing one form of this invention, and comprising a locking bar, an allan set screw, an allan wrench, a guard member, a shoulder pin, a padlock, and a key for said padlock;

Figure 6 is an enlarged sectional view showing the locking bar of this invention in section, with an allan wrench inserted in an allan set screw which is in tight contact with the pin surface of the shoulder pin, said wrench for adjusting said screw.

Figure 7 is an enlarged sectional view of the locking bar as shown in Figure 6, the wrench removed and the hasp of a lock arranged in an opening in said bar to prevent the insertion of an allan wrench.

The devices embodying the features of this invention may be attached to many standard forms of electrical switches and circuit breaker

structure as long as the manually operating lever has an opening therein.

In Fig. 1, the improved form of locking device is shown attached to a circuit breaker. The circuit breaker illustrated in Figures 1, 2, 3 and 4 is of the same general type as is disclosed in Patents No. 1,802,758 and 2,192,060 for illustrative purposes only. The details of the circuit breaker shown in Fig. 1 are not an essential part of this invention, but are merely shown by way of example. The circuit breaker illustrated in Figures 1, 2, 3 and 4 comprises a base 10 to which is secured a cover or casing member 11. The casing and base are of suitable material as desired and are formed to provide a chamber 12 in which is mounted the circuit breaker contact means, and the operating means therefor. A stationary contact 15 is mounted on the base at the forward end of the compartment. The stationary contact is electrically connected to a suitable terminal not shown. A movable contact 16 is secured to a contact carrying arm 20 at one end thereof. The other end of the contact carrying arm is secured to a channel shaped contact supporting frame (not shown) which is pivotally mounted between the side walls of a main frame 22 by means of a pin 24. A cradle member 26 is pivotally mounted at one end thereof on a pin 28 carried at the forward end of the main frame between the side walls thereof. Toggle links 30 and 32 interconnect the cradle member with the movable contact carrying frame. A U-shaped operating member 34 has the lower ends of its legs pivotally secured to the side walls of the main frame as indicated at 36. An overcenter spring 38 has one end thereof connected to the knee pivot 40 of the toggle linkage 30, and 32, and its other end secured to a lug 44 formed on the underside of the bight portion of said operating member. An operating handle 46 of insulating material is provided with a curved closure portion 48 which is secured to the top of the bight portion of the operating member. Said handle 46 has a hole 50 drilled therein parallel with its upper surface. The operating handle extends through an elongated slot 52 of rectangular shape provided in the cover 14.

The U-shaped bimetallic trip element 54 is connected to an outside terminal now shown. The other end of the bimetallic trip element is connected through a metallic supporting base 56 for the trip element, and a terminal 58, with a flexible conductor 60. The conductor 60 is electrically connected to the movable contact carrying arm 20. The upper end of the bimetallic trip element is provided with a latch portion 64 which is adapted to engage and hold a latch nose 66 formed on the free end of the cradle member 26. An angle piece 70 is secured to the underside of the curved portion of the operating handle 46 for engaging and moving the cradle member in a counter-clockwise direction about its pivot point 28 to reset the circuit breaker. For aiding in the extinction of the arcs which are formed incident to the opening of the circuit controlled by the breaker, an arc extinguishing device 72 of the spaced plate type is provided. The features of this extinguisher are not an important part of my invention and any suitable structure may be utilized.

The operation of the circuit breaker described above is briefly as follows: The circuit breaker is shown in the tripped position, and the operating handle must be moved to open position to reset the mechanism before the breaker can be closed

from this position. Movement of the operating handle 46 toward the left to its open position in which it is adjacent the edge 74 of the opening 52 in the casing causes the angle piece 70 of the handle 46 to engage and move the cradle 26 in a counterclockwise direction to a position in which the latch nose 66 is engaged and held by the latched portion 64 of the bimetallic trip element. In this position of the parts described, the movable contact is in its open circuit position. If the operating handle 46 is now moved to the right, to a position in which it is adjacent the edge 76 of the opening 52 in the casing, the overcenter spring will move the toggle linkage 30 and 32 to an extended position to cause the movable contact to move with a snap action into engagement with the stationary contact 15. Movement of the operating handle to its open circuit position in which it is adjacent the edge 74 of the opening 52 will cause the overcenter spring to break the toggle linkage 30 and 32 and thus move the movable contact 18 to an open circuit position with a snap action. With the movable contact 18 in its closed circuit position and the nose 66 of the cradle engaged and held by the bimetallic trip element, if an overload occurs on the circuit in which the contacts 18 and 15 are connected, the bimetallic trip element 54 will be heated by the overload current and bend in a direction away from the nose 66 of the cradle member to release the same. The release of the cradle member 66 causes the overcenter spring to break the toggle linkage and thus move the contact 18 to an open circuit position. This last operation takes place irrespective of the position of the operating handle 46. The release of the cradle 66 in response to an overload also effects movement of the operating handle 46 to an intermediate indicating position as shown in Fig. 1 to indicate that the breaker has been tripped open.

One form of the locking device of the present invention clearly illustrated in Figures 4, 6, and 7 and also more clearly shown in Figure 5 is a disassembled perspective view. Said device consisting of a metallic locking bar 82 having a lateral opening 83 adjacent its end 84 and a lateral opening 85 adjacent its end 86. Said bar also has a transverse opening 88 of circular cross section extending from its end 86 to said lateral opening 83, and passing through lateral opening 85. The section of the circular opening 88 between openings 83 and 85 is provided with internal threads. An allan set screw 89 with external threads is placed within the threaded section of opening 88, said screw having its closed end 90 extending toward said opening 83 and with its end having its key socket extending toward said opening 85. By this arrangement of said parts, one end portion of an allan wrench 92 can be inserted through the open end of opening 83 and arranged in the key socket of said allan set screw 89. As shown in Figure 6, when the pin portion 94 of a shoulder pin 96 is inserted within said lateral opening 83, said pin 96 can be secured in locking engagement with the wall of said opening 83 by screwing the end portion 90 of said set screw 89 into direct engagement with said pin portion 94; this being done by manipulation of said allan wrench 92. Should said shoulder pin 96 be tightly secured within said opening 83 and it is desired to prevent the insertion of an allan wrench 92 through opening 83 to contact said set screw 89, it is clearly shown in Figure 7 that the pivoted hasp 98 of a lock 99 may be positioned in the opening 85 blocking

the passage way to the threaded section of the opening 88. It is clearly shown in Figure 7 that the guard member 100 has a lateral portion 101 and an angular portion 102, said angular portion 102 provided with an opening 103. A key 105 is also shown in said Figure 7, said key to be used with said lock 99 in the usual manner.

The locking device described above may be attached to the breaker structure in the following manner. The end 95 of shoulder pin 96 may be inserted through opening 50 from the underside of the operating handle 46 and through opening 103 of guard member 100 if properly placed with its lateral portion 101 within the opening 52 of cover 14 and with its angular portion 102 against the upper surface 47 of handle 46. The end 95 of said pin 94 will extend beyond the exposed surface 102 of guard 100. The locking bar 82 may be placed upon said pin portion 94 by allowing the end portion 95 of said pin to extend entirely through the opening 83 of said bar. The bar 82 is then forced into tight engagement with portion 102 of said guard 100. With the bar 82 in position against said guard 100, and said guard 100 against said handle 46 the bar can be securely locked upon said pin 94 by turning said set screw 89 within the threaded portion of opening 88 until its end portion 90 is in contact with said pin 94; this turning action being accomplished by inserting said allan wrench 92 into the open end of opening 83 and arranging same within the socket of said set screw and then turning said wrench in a clockwise direction. After said pin 94 is locked within said bar 82, said allan wrench is removed. The operator then unlocks the padlock 99 with key 105 whereby the hasp 98 of said padlock 99 is free to pivot within said padlock 99. The free end portion 106 of the hasp 98 is then inserted into said opening 85 of said bar 82 whereby said free end 106 will extend beyond said bar 82 so that the padlock body portion 99 can be raised into engagement with said hasp and both portions locked together in a secure union due to the usual snap action of the padlock. With the padlock 99 and hasp 98 so arranged it is impossible for anyone to insert an allan wrench 92 into said opening 88 for contacting said set screw 89 to turn the same in a counterclockwise direction to remove the bar 82 from said pin 94.

When the locking device is arranged as described above, the operating handle cannot be moved any substantial amount. The locking device may be inserted in the opening either in the open position as shown in Figures 1, 2, 3 and 4 or in a reverse position so that the operating handle may be held against substantial movement in either its closed circuit position or open circuit position, whichever is desired. It is clearly shown in Figure 1 that the breaker is in tripped condition with movable contact 18 in open position. When the guard is inserted within the slot and locked against the operating handle in either "on" or "off" position, the handle can never be moved a sufficient amount to cause the contacts to be opened or closed.

This novel locking means as described above may be used with any standard lines of switches either of the current responsive or noncurrent responsive types as long as a hole is provided within the operating handle for the insertion of a shoulder pin, or the like, whereby the inserted pin can extend through the hole within the outwardly extending portion of said guard; said holes

in said handle and said guard should be substantially in alignment.

Although the foregoing description is necessarily of a detailed character, in order to define the structure, function and advantages of the invention it is to be understood that the specific terminology is not to be restricted or confining and that various arrangements of the parts and alternate combinations of elements may be resorted to without departing from the scope or spirit of the invention as herein claimed.

I claim:

1. The combination with a circuit interrupter having an oscillatable operating handle movable back and forth in a single plane to "on" and "off" positions and having a casing provided with a slot in which the operating handle is movable, said handle having an opening therethrough, of a rigid guard removably mountable in said slot in either of two opposite positions for contacting an inclined surface of said operating handle, said guard having an opening therethrough, of a shoulder pin member removably placeable through said openings arranged in said operating handle and said rigid guard, of a locking bar, said locking bar having an opening therethrough to receive one end of said pin member, and a securing means for locking said bar to said pin member.

2. The combination with a circuit interrupter having an oscillatable operating handle movable back and forth in a single plane to "on" and "off" positions and having a casing provided with a slot in which the handle is movable, said handle having an opening therethrough, of a rigid guard removably mountable in said slot in either of two opposite positions for contacting an upwardly inclined surface of said handle, said rigid guard having an opening therethrough, of a member removably placeable through said openings arranged in said handle and said guard, of a locking bar, said locking bar having an opening therethrough, and an adjustable securing means for locking said bar to said member.

3. The combination with a circuit interrupter having an oscillatable operating handle movable back and forth in a single plane to "on" and "off" positions and having a casing provided with a slot in which the handle is movable, of a rigid guard removably mountable in said slot in either of two opposite positions for contacting a surface of said handle, said handle and said rigid guard having aligned openings therethrough, of a member removably placeable through said aligned openings arranged in said handle and said guard, of a locking bar, said locking bar having an opening therethrough, and an adjustable securing means for locking said bar to said member.

4. The combination with a circuit interrupter having an oscillatable operating handle movable back and forth in a single plane to "on" and "off" positions and having a casing provided with a slot in which the handle is movable, of a rigid guard removably mountable in said slot in either of two opposite positions for contacting an inclined surface of said handle, said handle and said rigid guard having aligned openings therethrough, of a member removably placeable through said aligned openings arranged in said handle and said rigid guard, of a locking bar, said locking bar having an opening therethrough, of an adjustable securing means for locking said bar to said member, and a locking means engageable with said bar for preventing adjustment of said adjustable securing means.

5. The combination with a circuit interrupter having an oscillatable operating handle movable back and forth in a single plane to "on" and "off" positions and having a casing provided with a rectangular slot in which the handle is movable, of a guard removably mountable in said slot in either of two opposite positions for contacting an end portion of said slot and the upper inclined surface of said handle, said handle and said guard having aligned openings with each other therethrough, of a shoulder pin removably placeable through said aligned openings arranged in said handle and said guard, of a locking bar, said locking bar having an opening therethrough, of an adjustable securing means arranged adjacent the opening in said locking bar, said securing means for locking said bar to said shoulder pin, of a second opening within said bar, and a locking means arranged in said second opening within said bar for preventing adjustment of said securing means to unlock said bar upon said member.

6. The combination with a circuit interrupter having an oscillatable operating handle movable back and forth in a single plane to "on" and "off" positions and having a casing provided with a rectangular slot in which the handle is movable, of a guard removably mountable in said slot in either of two opposite positions for contacting an end portion of said slot and the upper inclined surface of said handle, said handle and said guard each having aligned openings with each other therethrough, of a shoulder pin removably placeable through said aligned openings arranged in said handle and said guard, of a locking bar, said locking bar having an opening therethrough, of an adjustable securing means arranged adjacent the opening in said locking bar, said securing means for locking said bar to said shoulder pin, of a second opening within said bar, and a locking means provided in the form of a lock body and with a pivoted hasp, said hasp shaped to extend through said second opening in said locking bar preventing access to said securing means whereby said pin may not be removed from said bumper guard and said operating handle when it is not so desired.

7. The combination with a circuit interrupter having an oscillatable operating handle movable back and forth in a single plane to "on" and "off" positions and having a casing provided with a rectangular slot in which the handle is movable, of a guard removably mountable in said slot in either of two opposite positions for contacting the upper inclined surface of said handle, said handle and said guard having aligned openings with each other therethrough, of a shoulder pin removably placeable through said aligned openings arranged in said handle and said guard, of a locking bar, said locking bar having an opening formed adjacent one end thereof, said locking bar having a larger opening formed adjacent the opposite end thereof, said locking bar having a transverse opening therein connecting said openings adjacent each end thereof, of an adjustable allan set screw in said transverse opening and arranged adjacent the smaller of said openings, said allan set screw for locking said bar to said shoulder pin, and of a locking means provided in the form of a lock body and with a pivoted hasp, said hasp shaped to extend through the larger opening at one end of said locking bar preventing access to said securing means whereby said pin may not

be removed from said bumper guard and said operating handle when it is not so desired.

8. The combination with a circuit interrupter having an oscillatable operating handle movable back and forth in a single plane to "on" and "off" positions and having a casing provided with a rectangular slot in which the handle is movable, of a guard removably mountable in said slot in either of two opposite positions for contacting the upper inclined surface of said handle, said handle and said guard having aligned openings therethrough, of a shoulder pin removably placeable through said aligned openings arranged in said handle and said guard, of a locking bar, said locking bar having an opening formed adjacent one end thereof, said locking bar having a larger opening formed adjacent the opposite end thereof, said locking bar having a transverse opening therein connecting said openings adjacent each end thereof, of an adjustable allan set screw in said transverse opening and arranged adjacent the smaller of said openings, said allan set screw for locking said bar to said shoulder pin, said allan set screw adjusted from one position to another by the manipulation of an allan wrench if and when inserted within said transverse opening, and of a locking means provided in the form of a lock body and with a pivoted hasp, said hasp shaped to extend through the larger opening at one end of said locking bar preventing access to said securing means, whereby said pin may not be removed from said bumper guard and said operating handle for unlocking the parts.

9. In a circuit breaker, a casing, contact means, means including a manually operated control handle member movable in an open circuit position and to a closed circuit position for causing corresponding movements of said contact means, said casing having an opening through which said control handle member extends, a guard removably positioned in said opening for contacting an inclined surface of said handle member, said guard and said handle member each having aligned openings therein, a shoulder pin removably placeable through said openings arranged in said guard and said handle member, a locking bar, said locking bar having an opening adjacent one end thereof through which the end of said pin may extend, and an adjustable securing means for locking said bar to said pin for preventing substantial movement of said control handle member while said guard is so positioned.

10. In a circuit breaker, a casing, contact means, means including a manually operated control handle member movable to an open circuit position and to a closed circuit position for causing corresponding movements of said contact means, said casing having a rectangular opening through which said control handle member extends, a guard removably positioned in said rectangular opening for contacting an inclined surface of said handle member, said guard and said handle member each having aligned

openings therein, a shoulder pin removably placeable through said openings arranged in said guard and said handle member whereby the end portion of said pin will extend outwardly therefrom, a locking bar, said locking bar having an opening in one end thereof through which the end of said pin may extend, and an adjustable allan set screw in said block for locking said bar to said pin for preventing substantial movement of said control handle member while said guard is so positioned, said guard being of angular formation having a horizontal portion and an upright portion angularly disposed with said horizontal portion.

15 11. In a circuit breaker, a casing, contact means, means including a manually operated control member movable to an open circuit position and to a closed circuit position for causing corresponding movements of said contact means, said casing having an opening through which said control member extends, a device removably mounted in said opening to prevent substantial movement of said control member, said device including means for quick attachment to or detachment from the edges of said opening, said device including a guard, a shoulder pin, a locking bar, an allan set screw, and a locking body having a pivoted hasp, said control member having a hole formed therein adjacent its uppermost end, said guard having a hole formed therein adjacent its uppermost end, said pin arranged to be placed through both of said openings and with its shoulder in contact with one side of said control member, said pin also arranged to extend through an opening in said locking bar, said allan set screw being arranged with said locking bar and adjustable so as to contact and secure said bar to said pin, and said locking body arranged whereby the hasp thereof prevents access to said allan screw to prevent adjustment or removal thereof when the parts are not to be unlocked.

12. In a circuit breaker, a casing contact means, means including a manually operated control member movable to an open circuit position and to a closed circuit position for causing corresponding movements of said contact means, said casing having an opening through which said control member extends, a device removably mounted in said opening to prevent substantial movement of said control member, said device including means for quick attachment to or detachment from the edges of said opening, said device including a guard with a horizontal portion and an upwardly extending portion, a shoulder pin, a locking bar means, an allan set screw, and a locking means for preventing detachment of said guard from the edges of said opening.
